UNITED STATES PATENT OFFICE.

ADELBERT W. R. SCHULTZ, OF CLARION, IOWA.

QUICK-CHANGE PUMP-JACK HEAD.

Application filed May 26, 1925. Serial No. 32,944.

This invention relates to pump jack heads adapted for use in connection with the ordinary farm water well pump.

It is a common expedient in pumping the wells of farms to provide a windmill for actuating an ordinary vertical pump and it is also a common expedient to provide means for actuating such pumps by a power drive from a gasoline engine, an electric motor or the like so that, at times when the wind is not sufficient to actuate the windmill, the pump may still be power actuated. Such combined wind and other power arrangement naturally necessitates the disconnecting of the pump rod or sucker rod from one power device and the connecting of the same to the other. It frequently happens that such changes have to be made one or more times every day and, where ordinary bolts and like connections are used the operation requires a considerable time and the use of wrenches or other tools.

The important objects of the present invention are to provide a novel and improved device for connecting the sucker rod of an ordinary well pump to the pitman or connecting rod of an ordinary power drive, capable itself of being driven by a motor such as a gasoline engine or electric motor, the connecting means being such that it may be quickly operated by hand and without the use of tools, the connecting also being of such character that it cannot become accidentally disconnected during the operation of the pump.

With these and other objects in view as will be hereinafter apparent, the invention consists of certain novel features of construction and combination of parts, one preferred form of which will be now described in detail and then specifically claimed, reference being had to the accompanying drawings, wherein:

Figure 1 is a side elevation of a pump showing the same located at the lower part of a windmill and illustrating the improved pitman arrangement.

Figure 2 is a section on the line 2—2 of the Figure 1.

Figure 3 is an enlarged detail side elevation of the upper part of the pitman and the sucker rod and showing the improved connection thereof the same being illustrated as closed in full lines and as opened in broken lines.

Figure 4 is a front view of the parts shown in Figure 3.

Figure 5 is a plan view of said parts.

Figure 6 is a section on the line 6—6 in Figure 4.

Figure 7 is a section on the line 7—7 of 60 Figure 5.

Figure 8 is a section on the line 8—8 of Figure 4.

Figure 9 is a detail perspective view of a swinging lock member used herewith. 65

The invention has here been shown as applied to an ordinary iron body pump illustrated in general at 10. This pump is equipped with the usual pump rod or sucker rod 11 and may be operated by ordinary 70 pump handle 12, as described. In order to provide for the motor drive of the pump there is provided, on the well head or casing 13, a frame 14 which is secured to the well head by bolts 15 and to the pump barrel by bolts 16. 75 Journaled in this frame is a shaft 17 whereon is mounted a belt pulley 18 adapted for the reception of an ordinary belt 19 of any suitable kind and leading from a motor, the latter not being deemed necessary here to be 80 shown. On this shaft 17 is fixed a pinion 20, which meshes with a gear 21 fixed on a shaft 22 also journaled in the frame 14. On each end of the shaft 22 is a crank disk 23 provided with a crank pin 24. The pitman is of built 85 up construction, consisting of a pair of rods 25 having their lower ends mounted on the pins 24 and their upper ends connected by a cross bar or cross casting 26, this casting being connected to the rods 25 by means of bolts 90 27 passing through bolt holes 28 in the upper ends of the rods 25. There are a series of these bolt holes in these rods so that the casting may be connected at a selected position to said rods. Extending forwardly from the front 95 face of the casting 26 is a lug 29 wherethrough passes a bolt having a cylindrical head 30 and having a reduced and threaded shank 31, the head engaging one side of the lug 29 and the shank passing through an opening in said lug 100 and having a nut 32 screwed thereon. Thus the head 30 forms a crank pin. Alined vertically above the lug 29 and projecting upwardly from the top of the casing 26 is an ear 33, a similar ear 34 also projecting upwardly in 105 spaced relation to the ear 33 so that a pivot pin 35 may be supported by these ears, being held therein by a suitable cotter 36. Mounted on the pin 35 between the ears 33 and 34 is a sleeve 37 carrying a locking plate 38 which is 110 connected to the sleeve by a curved shank 39. This locking plate is provided with a flat side

which bears against the face of the casting 36 when the locking plate is swung down into locking position as shown in full lines in Figure 6. The locking plate conforms in general 5 to the shape of the lug 29 and when in a locking position, lies parallel thereto and close to the end of the bolt head 30. This locking plate is provided with an operating handle 40. The pump or sucker rod 11 is provided 10 with an opening 41 which fits on the head 30. Thus, when the locking plate is swung upwardly, bolt head 30 may be slipped out of the opening 41, thus disconnecting the sucker rod from the power driven pitman. In order to 15 retain the plate 38 in its locking position the hub 37 is made somewhat shorter than the rods between the ears 33 and 34 and at one end is provided with a notch 42 adapted for engagement with a tooth 43 formed on a 20 spring washer 44. The locking plate, it will be noted, when in unlocking position is entirely clear of the sucker rod as can be seen in the dotted line positions shown in Figures 3 and 4. It will be noted that the casting 25 forms a head for the pitman.

It will be obvious that it is merely necessary, in the operation of the device to move the locking plate to the open position, adjust the sucker rod on the head 30 or slip the head out 30 of the opening 41 as required and then swing the locking plate to its locking position.

While one preferred embodiment of the invention has here been shown it will be obvious to engineers and others skilled in this art that 35 changes may be made in the detail and proportions of the device without departing from the principles. Accordingly it is to be understood that the invention is to be interpreted in accordance with the breadth of the claims 40 and not by the exact detail of construction herein shown and described.

Having thus described the invention, what is claimed as new, is:

1. A pitman and pump rod connection comprising a pitman having a head provided with 45 a projecting pin, a pump rod having an opening receiving said pin, a pivot pin carried by said head and parallel with the first pin, and a locking plate swingably mounted on said 50 pivot pin and movable into engagement with the pump rod in a locking position to prevent removal of said rod from said projecting pin.

2. A pitman and pump rod connection comprising a pitman head provided with a pivot 55 pin, a lug projecting from said head, a pin projecting laterally from said lug, a pump rod having an opening receiving said pin, and a locking plate swingably mounted on said pivot pin and movable into engagement with 60 the pump rod in a locking position to prevent removal of said rod from said projecting pin.

3. A pitman and pump rod connection comprising a pitman head, a lug projecting at right angles to said head, a pin projecting at right angles to said lug, a pair of ears projecting at right angles to said head above said lug, a pivot shaft supported in said ears parallel to said pin, a sleeve rotatably mounted on said pivot shaft, a locking plate projecting from said sleeve parallel to said lug, said plate being movable to cover and uncover the end of said pin, and an operating handle on said plate.

4. A pitman and pump rod connection comprising a pitman having a head provided with 75 a pivot pin and a laterally projecting pin, a pump rod having an opening therein receiving said laterally projecting pin, a locking plate swingably mounted on said pivot pin and movable into engagement with the pump 80 rod in a locking position to prevent removal of said rod from said projecting pin, and spring means to hold the locking plate releasably in locking position.

5. A pitman and pump rod connection comprising a pitman having a head provided with a projecting pin, a pump rod having an opening receiving said pin, a pivot pin carried by said head and parallel with the first pin, a locking plate swingably mounted on said 90 pivot pin and movable into engagement with the pump rod in a locking position to prevent removal of said rod from said projecting pin, and spring means to hold the locking plate 95 releasably in locking position.

6. A pitman and pump rod connection comprising a pitman head provided with a pivot pin, a lug projecting from said head, a pin projecting laterally from said lug, a pump 100 rod having an opening receiving said pin, a locking plate swingably mounted on said pivot pin and movable into engagement with the pump rod in a locking position to prevent removal of said rod from said projecting pin, and spring means to hold the locking plate 105 releasably in locking position.

7. A pitman and pump rod connection comprising a pitman head, a lug projecting at right angles to said head, a pin projecting at right angles to said lug, a pair of ears projecting at right angles to said head above said lug, a pivot shaft supported in said ears parallel to said pin, a sleeve rotatably mounted on said pivot shaft, a locking plate projecting from said sleeve parallel to said lug, said plate being movable to cover and uncover the end of said pin, an operating handle on said plate, and spring means to hold the locking plate 110 releasably in covering position.

In testimony whereof I affix my signature.

ADELBERT W. R. SCHULTZ.
